UNITED STATES PATENT OFFICE.

JOHN N. TOOKER, OF NEW YORK, N. Y.

INTERNAL-COMBUSTION MOTOR.

1,190,819.

Specification of Letters Patent. Patented July 11, 1916.

Application filed April 9, 1913. Serial No. 759,885.

To all whom it may concern:

Be it known that I, JOHN N. TOOKER, a citizen of the United States, residing in the borough of Brooklyn, county of Kings, 5 city and State of New York, have invented an Improvement in Internal-Combustion Motors, of which the following is a specification.

My present invention relates to an internal combustion motor and is an improvement upon that type of such motors in which one or more cylinders are employed with a corresponding number of pistons and the piston in each cylinder is driven on one 10 side only.

The object of my present invention is the provision of an internal combustion motor in which the piston is driven positively in both directions, an impulse being imparted 15 to the same from one side to drive it in one direction and a second impulse is imparted to the same from the other side thereof to drive it in the opposite direction, so that the weight of the motor per developed horse 20 power is substantially reduced one-half, with a corresponding reduction in size and consequent space necessarily occupied by the machine.

In carrying out my invention, the motor 25 preferably comprises a cylinder, a cylindrical piston in the cylinder, and an internal water jacketed head suitably supported and extending into the piston and forming therewith an internal combustion chamber, 30 providing for a compartment in which the second explosion takes place to drive the piston on its return stroke, the other end of the cylinder being constructed and acting in the same manner as is now common in 35 two-cycle motors.

In the drawing, Figure 1 is a central longitudinal cross section of an internal combustion motor embodying my present invention. Fig. 2 is a similar view taken 40 at right angles to the position of the parts as shown in Fig. 1. Fig. 3 is a cross section taken at about the line *c c*, Fig. 1, and Fig. 4 is a cross section taken at about the line *b b*, Fig. 1.

Referring particularly to the drawing, 45 my improved motor comprises a cylinder 10, which at its inner end is provided with a water cooled jacketed head indicated at 11. This water cooled jacketed head is 50 provided with a circular base 12 in which, on one side, is a water inlet 13, and on the

opposite, side a water outlet 14. Within the head 11 is a passage 15 extending from the inlet 13 through the extremity 16 of the jacketed head and to the outlet 14. The 55 cylinder 10 preferably rests on and is connected to the base of the water jacketed head, which in turn is supported upon and connected to the upper member 17 of the crank case, the lower member 18 of which 60 is suitably connected to any desired base. The upper or outer end of the cylinder, as is the common practice, is provided with a jacket 19 and the water inlet 20 on one side, and the water outlet 21 on the other 65 side adjacent to the end of the cylinder, making suitable provision, as will be understood, for cooling this end of the apparatus. Within the cylinder, I employ a piston 22, 70 which is preferably cylindrical. At its inner or lower end, the piston 22 is preferably provided with a flange 25 adapted to fit within and slide upon the inner surface of the wall 24 of the cylinder. The piston adjacent to its head is provided with suitable packing rings 26, and also the water cooled jacketed head 11, adjacent to its 75 extremity is provided with suitable packing rings 27, making a tight joint between the same and the inner walls of the piston, 80 and furthermore the flange 25 on the piston is also fitted with suitable packing rings 28, making a tight joint between the same and the walls 24 of the cylinder. Also at its lower or inner end, the piston, on opposite 85 sides thereof, is provided with lugs 29, in which there are bearings adapted to receive the pins 30 of the connecting rod 31, the opposite end of the connecting rod being connected to the crank 32 of the shaft 33, 90 which is journaled in bushings 34 placed in suitable bearings.

It will be noted that the connecting rod 31 is divided longitudinally, in order that the outer or piston end of the same may be connected to the piston and also that I prefer to provide a bushing 35 between the opposite end of the connecting rod and the pin of the crank arm, a suitable cap 36 being employed to connect and secure this 95 end of the connecting rod on the bushing 35.

On one side of the cylinder, and running longitudinally therewith is a rib, making provision for the inlet port 37 to the explosion chamber between the walls of the 100 cylinder and the piston at the upper or outer end of the motor, and in the walls of

the cylinder there are exhaust ports 38. In the piston wall there is an admission port 39 registering with an admission port 45 when the piston is in the position shown in Fig. 1, providing for the admission of the explosive mixture to the second combustion chamber between the interior of the piston and the head of the internal water cooled jacket 11. Adjacent to the inlet port 37, the piston is provided with a rib or deflector 40, and similarly adjacent to the inlet port 39 the end 16 of the internal water jacketed head is provided with a rib or deflector 41, the purpose and function of both of these ribs being to direct the passage or flow of the combustion mixture upwardly to effect an even distribution of the same in the explosion chamber. 42 and 43 indicate spark plugs or other ignition devices, the former of which is so placed as to communicate with the combustion chamber between the piston and the walls of the cylinder and the latter with the combustion chamber between the walls of the piston and the end of the internal water jacketed head.

It is also to be noted that in this construction, a mixing chamber 44 is provided, between the outer walls of the piston and the walls of the cylinder, for the explosion mixture supplied to the chamber between the inner walls of the piston and the end of the internal water jacketed head. It will further be noted that the exhaust ports are so placed as to be common to both explosion chambers. I wish also to direct attention to the fact that the internal water jacketed head is substantially U-shaped in cross section, making provision for necessary space for the reciprocating parts in the operation of the motor.

I claim as my invention:

1. In an internal combustion engine and in combination, a cylinder, a hollow piston therein forming a combustion chamber between its head and one end of the cylinder, there being a mixing chamber between the walls of the piston and a portion of the walls of the cylinder, a crank case, and a jacketed extension of the crank case extending into the said piston and forming a second combustion chamber with the interior thereof.
2. In an internal combustion engine and in combination, a cylinder, a hollow piston therein forming a combustion chamber between its head and one end of the cylinder, there being a mixing chamber between the walls of the piston and a portion of the walls of the cylinder, a crank case, and a jacketed extension of the crank case extending into the said piston and forming a second combustion chamber with the interior thereof, there being provided an inlet port from the mixing chamber to the said second combustion chamber, an inlet port from the crank case to the first combustion chamber, and an outlet port common to both the said combustion chambers.
3. In an internal combustion engine and in combination, a cylinder having bores of different diameters, a hollow stepped piston forming a combustion chamber between its head and that portion of the cylinder having the smaller bore and also forming a mixing chamber between its walls and the larger bore of the cylinder, a crank case, and a jacketed extension of the crank case extending into the piston and forming the second combustion chamber with the interior thereof.
4. In an internal combustion engine and in combination, a cylinder having bores of different diameters, a hollow stepped piston forming a combustion chamber between its head and that portion of the cylinder having the smaller bore and also forming a mixing chamber between its walls and the larger bore of the cylinder, a crank case, a jacketed extension of the crank case extending into the piston and forming the second combustion chamber with the interior thereof, there being provided an inlet port from the mixing chamber to the said second combustion chamber, an inlet port from the crank case to the first combustion chamber, and an outlet port common to both the said combustion chambers.
5. In an internal combustion engine and in combination, a cylinder, a hollow piston within the cylinder, and forming a combustion chamber with one end thereof, there being a mixing chamber associated with the walls of the cylinder and hollow piston, a crank case, and an integral jacketed extension of the crank case extending into the piston and forming a second combustion chamber with the interior thereof, there being provided an inlet port from the mixing chamber to the said second combustion chamber, an inlet port from the crank case to the first combustion chamber, and an outlet port common to both the said combustion chambers.
6. In an internal combustion engine and in combination, a cylinder, a hollow piston within the cylinder forming a combustion chamber with one end thereof, there being a mixing chamber associated with the walls of the cylinder and hollow piston, a crank case and an integral jacketed extension of the crank case extending into the piston and forming a second combustion chamber with the interior thereof.
7. In an internal combustion engine and in combination, a cylinder, a hollow piston within the cylinder and forming a combustion chamber with one end thereof, there being a mixing chamber within the cylinder, a crank case and an integral jacketed extension of the crank case extending into the piston and forming a second combustion chamber with the interior thereof.

8. In an internal combustion engine and in combination, a cylinder, a hollow piston within the cylinder forming a combustion chamber with one end thereof, there being a mixing chamber associated with the walls of the cylinder, a crank case and an integral jacketed extension of the crank case extending into the piston and forming a second combustion chamber with the interior thereof, there being provided an inlet port from

the mixing chamber to the second combustion chamber, an inlet port from the crank case to the first combustion chamber and an outlet port common to both combustion chambers.

Signed by me this 7th day of April, 1913.
JOHN N. TOOKER.
